US00D683360S

(12) **United States Design Patent** (10) **Patent No.:** **US D683,360 S**
Phelan et al. (45) **Date of Patent:** **** May 28, 2013**

(54) **DISPLAY SCREEN WITH ICON**

(75) Inventors: **Kieran M. Phelan**, Seattle, WA (US);
Lindsey R. Barchek, Seattle, WA (US)

(73) Assignee: **Microsoft Corporation**, Redmond, WA
(US)

(**) Term: **14 Years**

(21) Appl. No.: **29/386,782**

(22) Filed: **Mar. 4, 2011**

(51) **LOC (9) Cl.** **14-02**

(52) **U.S. Cl.**

USPC **D14/491**

(58) **Field of Classification Search**

USPC D14/485-495; 715/700-867

See application file for complete search history.

(57) **CLAIM**

The ornamental design for a display screen with icon, as shown and described.

DESCRIPTION

The FIGURE is a front view of a display screen with icon showing the new design.

The broken line showing of the display screen is for environmental purposes only and forms no part of the claimed design.
